UNITED STATES PATENT OFFICE.

JAMES A. BUTLER, OF WINTHROP, MASSACHUSETTS, ASSIGNOR TO FREDERICK E. NICKELS, OF DORCHESTER, MASSACHUSETTS.

LOCKING DEVICE FOR VOTING-MACHINES.

1,028,837.

Specification of Letters Patent. Patented June 4, 1912.

Application filed November 16, 1910. Serial No. 592,705.

To all whom it may concern:

Be it known that I, JAMES A. BUTLER, of Winthrop, in the county of Suffolk and State of Massachusetts, have invented a new and Improved Locking Device for Voting-Machines, of which the following is a specification, reference being had to the accompanying drawings, forming part thereof.

This invention has reference to improvements in locking devices for voting machines whereby a series of actuating devices may be locked against operation by or through the operation of one of said devices.

The object of this invention is to so construct a locking device for a mechanically operated voting machine adapted to register votes for several candidates to a single office, that the operation of the device through which a vote for one candidate for an office is registered automatically effects the locking of a series of similar actuating devices.

Other objects of the invention appear from the following description.

The invention consists in a series of actuating devices, for vote registering mechanism, any one of which may be operated by a voter, and means operated by the first device operated for locking all other of said devices against movement.

The invention also consists in such other novel features of construction and combination of parts as shall hereinafter be more fully described and pointed out in the claims.

Figure 1, represents a sectional plan view of a series of the improved locking devices taken on line 1—1 Fig. 2. Fig. 2, represents a sectional view of the same taken on line 2—2 Fig. 1, one of the ordinary registering devices being shown in position. Fig. 3, represents a view similar to Fig. 1, the parts being shown as in the locked position.

Similar numbers of reference designate corresponding parts throughout.

In the voting machine to which this improvement is particularly adapted, a series of vote registering mechanisms are arranged in vertical series and are provided with key operated rotatable devices through each of which its related registering mechanism is operated, once for each vote cast, by the rotation of the key operated device. Said several registering mechanisms of said series are intended to register votes for the several candidates for a single office and, hence,

precaution should be taken to prevent the operation of several of the registers by a single voter.

In carrying this invention into practice, I construct a machine having the front plate 5 and the back plate 6 secured together by the posts 7, 7 and carrying between them the rotatable hubs 8, 8 each having at one end the key hole 9 and at the other the square spindle 10 while, in the body of the hub 65 are the segmental depressions 11 open at the periphery of the hub. On blocks 12, 12 secured to the plate 5 are pivotally mounted links 13, 13 having rounded ends 14, 14 to each pair of which is pivoted the lock bar 15 having the upper squared end 16 and the lower curved end 17 which, at rest, is held in contact with the end 16 of the next lower bar 15 by the retractive action of the spring 18 connected with said bar 15 and some fixed part of the machine.

Pivotaly mounted on the studs 19, 19, extending from the back plate 6 are the arms 20, 20, of which one is provided for each hub 8 toward which it is pressed by the spring 21, said arms 20 each having the curved members 22 the end of which is adapted to be received by one of the depressions 11, 11 of its related hub 8, and the longer member 23 having the pin or stud 24 which is so positioned that in its movement against the action of spring 21 it just clears the end 16 of its related lock bar 15. The lower of said series of lock bars 15 is furnished with the stud 25 which is engaged with the stop 26 fixed on the plate 5 whereby the downward movement of said lowermost lock bar 15 is prevented. Above the upper of said series of lock bars 15 is positioned the stop 27 which resists undue strain exerted on the pin 24, when in the locking position, by the attempt to lift said series of lock bars 15 or any of them.

In operating the machine, a key is inserted in the keyhole 9 of one of the hubs 8, and a rotative movement is given to said key to rotate the particular hub 8 with which the key is engaged and to thus actuate the vote registering mechanism, consisting of the toothed rack 30, movable longitudinally by being contacted by the opposite lugs 31 of the hub 8, with which the spindle 10 is engaged. As the hub 8 rotates, the surface of its depression 11, gradually enlarging to the periphery of the hub 8, moves

against the end of the curved member 22 of its related lever 20 and effects the swinging of said lever and its member 23, against the action of its spring 21, whereupon the pin 24 is moved into line with the series of lock bars 15; in the case of the upper locking device, said pin moves over the end 16 of the uppermost of said series of bars 15 and prevents the upward movement of all of said 10 lock bars while in such position. In the case of the lower of said lock bars 15, the pin 24 of the particular lever 20, in swinging above the end 16 of its related lock bar 15, bears against the curved end 17 of the 15 lock bar 15 next above and moves upward said lock bar and all the corresponding lock bars thereabove, so that their upper ends 16 are above the path of movement of their related locking pins 24 whereby the rotation 20 of the hubs 8 of said upper devices is prevented through the interception of the pins 24 by the edges of said lock bars 15 whereby the ends of the curved members 22 are held in locking engagement with the depression 25 11 of their respectively related hubs 8. If said lock bar 15, directly engaged by its related pin 24, is above the lowermost lock bar of the series all of said lock bars 15 therebelow are locked by the engagement of 30 said pin 24 with the end 16 of its related lock bar, so that said lock bars cannot move upward and hence none of the pins therebelow can ride between the lock bars 15 as 35 shown in Fig. 3 of the drawing and thereby the backward swing of lever 20 is prevented.

While I have herein accentuated the curves 17 of the lock bars 15, it is to be understood that said ends are preferably

curved only to an extent that will enable said ends to ride up on to the related pins 24. 40

Having thus described my invention I claim as new and desire to secure by Letters Patent.

1. A device of the nature described comprising an actuatable device, a slideable rack 45 operatively positioned with respect thereto, a lever interlocking with said device, a locking bar adapted to be engaged and locked by said lever in its movement toward the voting position and a second lock bar related to the 50 first mentioned lock bar and adapted to be moved by the lever of the first lock bar to a position to intercept the lever, of the said second lock bar, in its movement toward the unlocking position; and said lock bars being 55 movably-mounted on pivoted supports.

2. The combination of a series of rotatable hubs, and a lever pivotally mounted adjacent each of said hubs and having two members, of which one interlocks 60 with said hub and is moved by the rotation of the hub to swing said lever, and the other of said members has a riding pin, of a series of approximately contacting lock bars related to said series of hubs and pivotally mounted on movable supports, each of said lock bars having a curved lower end with which the riding pin of said second lever member is adapted to coöperate to lift said lock bar from its normal position, 65 whereby said pin enters between two of said lock bars. 70

JAMES A. BUTLER.
